UNITED STATES PATENT OFFICE.

MAX GOLDSSTONE, OF NEW HAVEN, CONNECTICUT.

BURGLAR ALARM.

Application filed August 15, 1921. Serial No. 492,371.

To all whom it may concern:

Be it known that I, MAX GOLDSSTONE, a citizen of the United States, residing at New Haven, in the county of New Haven and State of Connecticut, have invented certain new and useful Improvements in Burglar Alarms, of which the following is a specification, reference being had therein to the accompanying drawings.

10 My invention relates to improvements in burglar alarms referring particularly to the type designed to be applied to either a door or window.

15 It is the object of this invention, among other things, to provide a simple and convenient alarm device that may be produced at the minimum cost, be readily applied to either a door or window and will sound an alarm as the result of the minimum opening

20 movement of either said window or door.

To these and other ends my invention consists in the alarm device having certain details of construction and combinations of parts as will be hereinafter described and

25 more particularly pointed out in the claims.

Referring to the drawings in which like characters of reference designate like parts in the several figures:

Figure 1 is an elevation of a fragmentary 30 portion of a door and its adjacent parts with my improved alarm device attached thereto;

Figure 2 is a plan view thereof the door and adjacent parts being in section;

35 Figure 3 is a similar plan view showing the relative arrangements of the parts for a door that opens outwardly; and

Figure 4 is a view illustrating my improved device connected with the upper and 40 lower sashes of a window frame, the sashes being shown in vertical section.

In the drawings 10 designates the bell which may be of any one of the common types well known to the art and is operated by a plunger 11 having a head 12 thereon. Connected with this bell by screws 13 is a separable plate 14. This plate, for convenience in attachment, is provided with two notches 15 through which project the 45 screws 13. Upon the opposite side of the plate is a slot 16 opening outwardly and a slot 17 that opens inwardly. This plate is separably secured in position by the screws 18 that pass through the slots 16 and 17. 50 Both screws are preferably positioned before the plate 14 is connected therewith by

first engaging one of the screws 18 with the slot 16 and then using this screw as a pivot, swing the plate until the other screw 18 enters the slot 17, then by turning the screws 60 the plate is secured against movement.

As shown the opposite edges of the plate 14 occupy different planes, see Figures 2, 3 and 4. As a result of this shaping of the plate one edge thereof is in parallel relation with the bell and the other with the member to which it is secured.

In Figures 1 and 2 this plate is secured to the door frame 19, in Figure 3 to the door 20 and in Figure 4 to the upper plate 21 70 of the lower window sash 22.

The numeral 23 designates a lever, having thereon a cam lug 24 provided with two cam faces 25 and 26 and the outer end terminating in a stop 27. This lever is pivotally connected with a plate 28 upon the stud 29 having a nut 30 threaded thereon, either substantially midway between the ends thereof as shown in Figures 1, 2 and 3 or near one end, as shown in Figure 4. Nut 80 30 has the usual polygonal portion whereby it may be rotated with a wrench and also with one or more openings 31 whereby it may be rotated by a pin, if the quarters are cramped for a wrench, which might 85 occur when the same is attached to a window frame.

The plate 28 is secured in position in any convenient manner, the means herein shown being the screws 32. A stop 33 fixed in the 90 plate 28 limits the rotary movement of the lever 23 so that in one position it occupies a position at substantially a right angle to the plate.

A convenient means for manipulating the 95 lever 23 is provided by a knurled button 34 threaded onto a screw 35, which is separably connected with the lever 23. The diameter of screw 35 is substantially the same as that of stud 29, so that the relative positions of 100 the stud and screw may be interchanged, in which case the button 34 occupies a position near the outer end of the lever as in Figures 1 to 3 inclusive, and substantially midway between its end as in Figure 4. In 105 Figures 1 and 2 my device is shown as applied for operation in connection with a door that opens inwardly. When desired that the alarm device should be placed in operative position, the lever 23 is swung 110 upon its pivot mounting until it contacts with the stop 33 when the cam lug is in the

path of movement of the plunger head 12. Then as the door 20 is moved, the cam face 26 is brought up against the plunger head 12 and the plunger is pushed inwardly, thus 5 sounding the alarm. In Figure 3, the operation is the same with the exception that the bell 10 is attached to the door and the lever 23 connected with the frame 19, this being a door that opens outwardly.

10 With any slight movement of the door upon its mounting, the plunger head 12 is moved across the face of the cam 25, thus pushing the plunger 11 inwardly and sounding the alarm. The stop 27 prevents the 15 head 12 from riding off the cam face 25, but does not prevent the continuous ringing of the bell, if the door is held in its moved position.

In Figure 4, the mechanism is applied to 20 a window frame in which case the button 34 and screw 35 are moved from the position shown in the other figures and the lever 23 is then pivotally connected with the plate 28 by the stud 29 passing through the same 25 hole in the lever previously occupied by the screw 35, and the screw 35 passing through the hole in the lever previously occupied by the stud 29. A spring 36 is now connected with the lever 23 to prevent rattling of the 30 parts and the outer end of the lever from prematurely engaging the plunger head 12. Movement of either the upper sash 37 or the lower sash 22 causes the outer end of 35 the lever 23 to contact with the plunger head 12, thereby causing the bell to ring and sound the alarm.

When not in use the lever 23 is moved in such relation to the plate 28 as to permit free movement of the door and the window 40 sashes without sounding the alarm.

Thus it will be seen that my improved device may be attached in position for operation by the movement of the door, whether moving inwardly or outwardly and 45 also with a window with the minor shifting of some of the parts.

Within the range of the appended claims 50 minor changes and alterations may be made in the details of my improved device and I therefore do not limit myself to the exact construction herein shown and described.

What I claim as new and desire to secure by Letters Patent, is:

1. A burglar alarm for attachment to a 55 structure having two parts, one movable relatively to the other, and comprising an alarm bell actuated through a push mechanism connected with one of said parts; a plate connected with the other of said parts; 60 a lever; means for connecting said lever with said plate, whereby it may be held in a position relatively thereto, either in the path of said push mechanism or out of the path thereof, as may be desired; and a cam 65 member connected with said lever and dur-

ing its movement engaging said push mechanism.

2. A burglar alarm comprising an alarm bell actuated through a push mechanism; a plate connected with a part other than that 7 to which the alarm bell is connected; a lever movably connected therewith; and a cam member connected with said lever and during its movement engaging said push mechanism, the means for connecting said 7 lever to said plate being such that the points of connection therewith may be varied.

3. A burglar alarm comprising an alarm bell actuated through a push mechanism; a plate connected with a part other than that 8 to which the alarm bell is connected; a lever movably connected therewith; and a cam member connected with said lever having two cam faces thereon, and during its movement engaging said push mechanism, 8 the means for connecting said lever to said plate being such that the point of connection therewith may be varied.

4. A burglar alarm comprising an alarm bell actuated through a push mechanism; a plate connected with a part other than 9 that to which the alarm bell is connected; a lever movably connected therewith; and a cam member connected with said lever having a stop thereon, and during its movement engaging said push mechanism, the means for connecting said lever to said plate being such that the point of connection therewith may be varied.

5. A burglar alarm comprising an alarm 1 bell actuated through a push mechanism; a plate connected with a part other than 1 that to which the alarm bell is connected; a lever movably connected therewith; and a cam member having two cam faces thereon and a stop at one end thereof connected 1 with said lever and during its movement engaging said push mechanism, the means for connecting said lever to said plate being such that the point of connection therewith may be varied.

6. A burglar alarm comprising an alarm bell actuated through a push mechanism; a plate connected with a part other than 1 that to which the alarm bell is connected; a lever; means for movably connecting said lever to said plate at different points along its length; a cam member connected with 1 said lever and during its movement engaging said push mechanism, and means for moving the lever upon its mounting.

7. A burglar alarm comprising an alarm bell actuated through a push mechanism; a plate connected with a part other than 1 that to which the alarm bell is connected; a lever; means for movably connecting said lever to said plate at different points along 1 its length; a cam member connected with said lever and during its movement engaging said push mechanism; and means for 1

moving the lever relatively to said plate that is interchangeable with the means for connecting the lever to said plate.

8. A burglar alarm comprising an alarm bell actuated through a push mechanism; a plate for securing said alarm bell in a fixed position, constructed with two slotted edge portions that occupy different relative planes, the slots in one edge being substantially parallel with each other and the slots in the opposite edge being at substantially

a right angle to each other; a second plate connected with a part other than that to which the alarm bell is connected; a lever movably connected with said second plate; and a cam member connected with said lever and during its movement engaging said push mechanism and actuating said bell. 15

In testimony whereof, I have hereunto affixed my signature.

MAX GOLDSTONE.
